UNITED STATES PATENT OFFICE

149,939

DESIGN FOR A COMBINED SPOON AND BOTTLE OPENER

Bert C. Failing, Baker, Calif.

Application January 7, 1947, Serial No. 135,981

Term of patent 7 years

(Cl. D44—29)

To all whom it may concern:

Be it known that I, Bert C. Failing, a citizen of the United States, residing at Baker, in the county of San Bernardino and State of California, have invented a new, original, and ornamental Design for a Combined Spoon and Bottle Opener, of which the following is a specification, reference being had to the accompanying drawing, forming part thereof.

The figure is a perspective view of a combined spoon and bottle opener, showing my new design.

I claim:

The ornamental design for a combined spoon and bottle opener as shown.

BERT C. FAILING.
